UNITED STATES PATENT OFFICE.

FREDERICK WILLIAM THOMSON, OF FORT WILLIAM, ONTARIO, CANADA.

DIPPER-DOOR.

986,522.

Specification of Letters Patent.

Patented Mar. 14, 1911.

Application filed July 6, 1910. Serial No. 570,649.

To all whom it may concern:

Be it known that I, FREDERICK WILLIAM THOMSON, a citizen of Canada, residing at Fort William, in the Province of Ontario, 5 Canada, have invented a new and useful Dipper-Door, of which the following is a specification.

This invention has relation to doors especially adapted to be used upon dippers 10 when employed for dredging or submarine purposes and it consists in the novel arrangement and configuration of its parts as hereinafter described.

At the present time it is a common practice to use a plane or flat door upon a dipper when the same is employed for dredging purposes and it not infrequently happens that the door closes against the bottom of a dipper at the same time that the door 20 strikes the surface of the water and frequently the incident shock without the possibility of rebound causes the door to break and go to pieces and at other times the shock is sufficient to bend or warp the door so that 25 it does not properly fit against the adjacent parts of the dipper.

It is the object of the present invention to eliminate this objectionable feature in a great measure and this is done by providing 30 a door of peculiar configuration especially adapted to enter the water by spreading the same rather than pushing a volume of water bodily away from the dipper as it is lowered.

With the above object in view the dipper 35 door is provided with a convex bottom side and a concave top side and is further provided with an impressed groove through which the latch bolt may move.

In the accompanying drawings,—Figure 40 1 is a side elevation of a dipper with the dipper door shown in section. Fig. 2 is a bottom plan view of the dipper door. Fig. 3 is a rear edge elevation of the dipper door.

As shown in the accompanying drawing, 45 the door 1 is formed of material which is approximately of the same transverse thickness throughout and the said door is stamped or otherwise formed with a convex bottom side and a concave top side. An 50 upwardly disposed channel or groove 2 is formed in the door 1 in the vicinity of its free edge and extends from a point approximately at the middle of the door to the edge thereof. A guide 3 is located in the vicinity 55 of the free edge of the door 1 and a latch

bolt 4 passes through the said guide and also traverses the length of the groove 2 and the inner portion of the said latch bolt passes through a guide 5 provided upon the door 1 in the vicinity of the hinged edge thereof. 60 A recess 6 is formed in the door 1 above the guide 3 and friction rollers or elements 7 are located in the said recess 6 and bear against the upper edge of the latch bolt 4. A roller 8 is journaled in the guide 5 and 65 supports the inner end portion of the said latch bolt 4. Any suitable means may be provided for moving the latch bolt 4 longitudinally and a dipper is provided in the vicinity of its lower edge with a keeper 9 70 adapted to receive the end portion of the said latch bolt in the usual manner. From the above description it will be seen that when the door 1 is closed at its edges against the bottom of the dipper, the dipper as an 75 entity is provided with a rounded end and consequently should the dipper be lowered into the water and strike the surface of the same, the water will be spread or forced laterally away from the sides of the dipper and 80 there will be slight tendency to force a volume of water in the same direction in which the dipper is moving. Therefore the configuration of the door serves as means for parting the water to permit the entrance of 85 the dipper and consequently unnecessary impact is avoided. Furthermore as the dipper approaches the bottom the lower portion of the latch bolt 4 is protected by the sides of the groove 2 and should the bottom come in 90 contact with rock or earth, the said latch bolt is protected to such an extent as to preclude the possibility of bending the same out of shape to prevent its operation. Furthermore the peculiar configuration of the 95 door braces the door structure against all strains to which it will be subjected and increase the carrying capacity of the dipper.

Having described the invention what I claim as new and desire to secure by Letters 100 Patent is:—

1. In combination with a dipper a door hingedly attached thereto and adapted to close at its edges against the end of the same and having a convex lower side. 105
2. In combination with a dipper, a door hingedly attached thereto and adapted to close at its edges against the end of the same and having a convex lower side provided with a groove extending approximately 110

from the middle of the door to its free edge, and a latch bolt slidably mounted in said groove.

3. In combination with a dipper a door hingedly attached thereto and adapted to close at its edges against the end of the same, said door having a convexed lower side provided with a groove extending from a point approximately at the middle of the door to the free edge thereof, a latch bolt arranged to move along said groove, guides provided

at the opposite edge portions of the door for the latch bolt and anti-friction devices located at the guides and adapted to bear against the edges of the latch bolt.

In testimony that I claim the foregoing as my own, I have hereto affixed my signature in the presence of two witnesses.

FREDERICK WILLIAM THOMSON.
